UNITED STATES PATENT OFFICE.

GEORGE W. BROWN, OF GALESBURG, ILLINOIS.

CORN-PLANTER CHECK-ROWER.

SPECIFICATION forming part of Letters Patent No. 244,178, dated July 12, 1881.

Application filed December 3, 1880. (Model.)

To all whom it may concern:

Be it known that I, GEORGE W. BROWN, a citizen of the United States, residing at Galesburg, in the county of Knox and State of Illinois, have invented certain new and useful Improvements in Corn-Planter Check-Rowers; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

15 My invention relates to that class of check-rower attachments to corn-planters in which the power for actuating the seed-slides is obtained by contact of the moving machine with knots or tappets on a fixed check-row wire or cord; and the nature thereof consists in certain improvements in the construction and combination of parts of the devices which receive motion from the check-row chain and impart motion to the seed-slides of the planter, 20 and also in improvements in the construction of the check-row chain, hereinafter described.

25 In the accompanying drawings, which illustrate my invention, and in which the similar letters used as marks of reference apply to like parts in all the figures, Figure 1 is a perspective of a construction embodying my invention. Fig. 2 is a top plan of the parts beneath the upper plate. Fig. 3 is same plan as Fig. 2, but the parts shown in different relative positions therefrom. Fig. 4 is a sectional elevation in line $\alpha\alpha$ in Fig. 3. Fig. 5 is a perspective of the lower oscillating deflector. Fig. 6 is a perspective of the upper oscillating deflector, bottom side upward. Fig. 7 is a perspective of one of the oscillating arms. Fig. 8 is a sectional plan of a knot, showing its attachment to check-row chain.

30 The construction and relative arrangement of the parts of the improvement and the adjacent parts of the general machine in which said improvements may be incorporated are as follows:

35 Letter A represents a bar common to this class of check-rowers, which bar extends across the planter and has fixed to each of its projecting ends a base-plate, B, each of which base-

plates carries a set of the working parts of my improvement, one only of which is shown in the drawings and hereinafter described, as the other is a duplicate thereof in all essential features.

40 C C' are cam-arms, duplicates of each other, and each bent so that their ends c are about at right angles with their ends c' . The cam-arms C C' are journaled at their bends c'' to the plate B in such manner that the heads E E' on their ends c' respectively are confronting each other and at a short distance from each other. The confronting faces of the heads E E' are convex, and each has a longitudinal 45 groove, e , terminated at its rear end by a semicircular shoulder, e' , with a semicircular groove, e'' , in its outer side, as shown at Fig. 7. The ends c of cam-arms C C' are connected by a link, c''' , and one of them has a stud, f , to which 50 one end of a rod or link, F, is connected, which extends across the planter, and is connected at its other end with a similar oscillating arm connected with the similar set of devices at the other end of the bar A. (Not shown in the drawings.) The link F is also connected with the seed-slide-operating bar. (Not shown.)

55 G is an oscillating check-row-chain deflector, formed of a lower plate, G', pivoted at its rear end, at g , to the plate B, and an upper plate, G'', supported a short distance above it on studs H H'. The opposite sides g' of the plate G' are concave, and a rib or projection, g'' , extends lengthwise on its upper side. The rib g'' has a forward pointed end formed by inclined 60 converging faces g''' g'''' , and its rear end is also tapering, as shown in the drawings. The plate G'' is divided lengthwise, or formed in two parts, with a space, h , between them, and each part has a rib, g'' , projecting from its lower 65 side down to a short distance from the rib g'' , the contours of the sides of which ribs correspond exactly with the contours of the sides of the rib g'' on the lower plate, G', which sides are immediately beneath each upper rib, g'' , 70 respectively, so that the upper and lower ribs, g'' , form a deflector, as hereinafter described, located interjacent or between the heads E E'. The plate G extends over and rests close above the heads E E'.

75 I I' are lugs or studs projecting upward from the plate A in rear of the studs H'.

J J are wings or flanges projecting upward from the plate A, and located with their converging ends close in front of the plate G, and have a recess, j, between their connected ends.

5 K is the ordinary check-row-chain guide-pulley, located adjacent to a guide-arm, L, on the forward end of the plate A.

M is the check-row chain or wire, formed of sections m of wire, with a spherical or otherwise 10 suitably-shaped knot or tappet, N, secured at the unions of each section m with the adjacent section, as follows: The tappets N have a central hole, n, with enlarged ends, n'. The adjacent ends of two sections of wire m are 15 passed through the holes n and each coiled upon the other and the coils m' drawn within the enlarged ends n' of the holes n, as shown at Fig. 8, thus securing the ends of the wire sections to each other and the tappets at the union 20 of the sections.

To commence planting, the wire M between two of the tappets is placed over and parallel with the space h between the two sides of the plate G'', so that it may drop down and between the heads E E', and either at one side 25 or resting on the lower rib, g'', and in the recess j. Supposing the heads E E' now to be in the relative positions shown at Fig. 2 and the machine to be moved in the direction 30 shown by the arrow, the first tappet, N, will be guided by the recess j and deflected by the faces g''' on the upper and lower ribs, g'', and thrown into the grooved adjacent side of the head E, where it will strike the shoulder e' and 35 force the head E backward, swinging the cam-arm C, and by means of the link c''' swinging the cam-arm C', and thereby throwing the head E' forward into the position shown at Fig. 3. The convex cam-face of the head E', in 40 swinging forward, as last described, came in contact with the concave side g' of the plate G', and thereby swung the plate G over to the position shown at same figure, and in such 45 position that the face g'''' of the ribs g'' will deflect the next succeeding tappet so as to come in contact with the shoulder e' of the head E' and swing it backward, and thereby swing the head E forward again, ready for the action of the next succeeding tappet. The cam-face 50 of the head E, in swinging forward, will swing the plate G back to the position shown at Fig. 2 by acting on its adjacent concave side. In swinging the head E backward the shoulder e' will be thrown away from the rib g'', and the 55 wire M, being held from deflection with it by the stud I, will release the tappet from the shoulder e' when the head E has reached the end of its throw, as limited by a stud, H. The tappets are released from the head E' by the 60 other stud, H', in a similar manner to the release from the head E. While the tappets are in contact with the shoulders e' the wire of the check-row chain will rest in the groove e''. The wire of the check-row chain may move 65 laterally as required between the upper and lower ribs, g''. At every throw or swing of the

cam-arms C C' a movement will be given the corn-planter seed-slides in the evident manner.

The check-row chain is stretched and the 70 planter moved in relation to it in the ordinary manner, and need not be described here.

I claim—

1. In combination with a knotted check-row chain, oscillating bent cam-arms adapted to 75 actuate the seeding devices, and having ends with confronting faces on which the knotted check-row chain acts, substantially as and for the purpose specified.

2. In combination with the bent arms C C', 80 having cam-heads E E', respectively, with confronting faces on which the knotted check-row chain acts, the interjacent plate G, adapted to be oscillated by the oscillations of the cam-arms, substantially as and for the purpose 85 specified.

3. In combination with the arms C C', having heads with grooves and shoulders e', on which the knotted check-row chain acts, the interjacent deflector g'', having faces g''' g''', 90 adapted to deflect the tappets to the cam-arms, substantially as and for the purpose specified.

4. The combination, with bent cam-arms having confronting faces on which the knotted check-row chain acts, of an interjacent deflector 95 adapted to deflect the tappets and direct them alternately to each of said arms.

5. The combination, with bent cam-arms having confronting faces on which the knotted check-row chain acts, of an interjacent swing- 100 plate adapted to be actuated by said bent cam-arms alternately.

6. Bent cam-arms C C', connected at one end by a link, c''', and their other ends provided with heads E E', in combination with a 105 knotted check-row chain which passes between the heads E E', substantially as and for the purpose specified.

7. In combination with the arms C C', having heads with confronting grooved faces and shoulders e', the lugs I I', adapted to hold the check-row chain while the heads E E' swing backward to release the tappets from the shoulders e', substantially as and for the purpose 110 specified.

8. The lugs I I', in combination with the swinging cam-arms and with the swinging deflector located between the grooved ends of the cam-arms, substantially as and for the purpose 115 specified.

9. In combination with the cam-arms having heads E E', with confronting faces, the swinging ribs g'', adapted to hold the tappets on the check-row chain in contact with the cam-arms, substantially as and for the purpose 125 specified.

10. In combination with the swinging cam-arms having heads E E', constructed substantially as described, the guide-flanges J, with recess j for the passage of the check-row chain, 130 substantially as and for the purpose specified.

11. The swinging cam-arms having heads

with confronting faces, in combination with the swinging interjacent plate G, with ribs g'', substantially as and for the purpose specified.

12. In combination with the swinging cam arms, the interjacent plate G, formed of an upper and lower part, and its upper part formed in halves, with a space between them, through which the check-row chain may be lowered into working position, substantially as and for the purpose specified.

13. A check-row chain formed of short sections of wire, with their adjacent ends inserted through holes in tappets, and coiled upon each

other, to hold the tappets to unite the sections, substantially as and for the purpose specified. 15

14. A check-row chain formed of short sections of wire, with their adjacent ends inserted through holes in the tappets and coiled upon each other within the tappet, substantially as and for the purpose specified. 20

In testimony whereof I affix my signature in presence of two witnesses.
